(57) **CLAIM**

The ornamental design for an eyewear case, as shown and described.

DESCRIPTION

FIG. 1 is a front view of an eyewear case (e.g., a protective cover for eyewear, such as eyeglasses, smart glasses, sunglasses, safety glasses, or any suitable combination thereof), showing our new design, in a first condition with a lowered latch;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a top-front-right perspective view thereof;

FIG. 8 is a top-front-left perspective view thereof;

FIG. 9 is a top-rear-left perspective view thereof;

FIG. 10 is a top-rear-right perspective view thereof;

FIG. 11 is a bottom-front-right perspective view thereof;

FIG. 12 is a bottom-front-left perspective view thereof;

FIG. 13 is a bottom-rear-left perspective view thereof; and

FIG. 14 is a bottom-rear-right perspective view thereof.

FIG. 15 is a front view of an eyewear case, showing our new design, in a second condition with a raised latch;

FIG. 16 is a rear view thereof;

FIG. 17 is a right side view thereof;

FIG. 18 is a left side view thereof;

FIG. 19 is a top view thereof;

FIG. 20 is a bottom view thereof;

FIG. 21 is a top-front-right perspective view thereof;

FIG. 22 is a top-front-left perspective view thereof;

FIG. 23 is a top-rear-left perspective view thereof;

FIG. 24 is a top-rear-right perspective view thereof;

FIG. 25 is a bottom-front-right perspective view thereof;

FIG. 26 is a bottom-front-left perspective view thereof;

FIG. 27 is a bottom-rear-left perspective view thereof; and

FIG. 28 is a bottom-rear-right perspective view thereof.

The shade lines show surface contour.

The wordmark “SPECTACLES” forming part of the claimed design is a registered trademark of Snap Inc.
